G. H. GOUGER,
SECTIONAL SQUARE.
APPLICATION FILED JAN. 21, 1914.

1,124,224.

Patented Jan. 5, 1915.

UNITED STATES PATENT OFFICE.

GEORGE H. GOUGER, OF CHARLOTTE, NEW YORK.

SECTIONAL SQUARE.

1,124,224.

Specification of Letters Patent.

Patented Jan. 5, 1915.

Application filed January 21, 1914. Serial No. 813,506.

To all whom it may concern:

Be it known that I, GEORGE H. GOUGER, a citizen of the United States, residing at Charlotte, in the county of Monroe and 5 State of New York, have invented new and useful Improvements in Sectional Squares, of which the following is a specification.

The invention relates to tools, and more particularly to the class of sectional squares 10 for carpenters' use.

The primary object of the invention is the provision of a square wherein it is made of sections separable to permit the use thereof as a try-square and as a straight rule.

Another object of the invention is the provision of a square of this character wherein the parts when united are assembled in a novel manner and held fast to avoid accidental separation thereof when in 20 use.

A further object of the invention is the provision of a square of this character which is extremely simple in construction, strong, durable, and inexpensive in manufacture.

With these and other objects in view, the invention consists in the construction, combination and arrangement of parts as will be hereinafter fully described, illustrated in the accompanying drawing, and pointed out 30 in the claims hereunto appended.

In the drawing:—Figure 1 is a top plan view of a square constructed in accordance with the invention. Fig. 2 is a top plan view of one section removed. Fig. 3 is a 35 similar view of the other section removed. Fig. 4 is a sectional view on the line 4—4 of Fig. 1. Fig. 5 is a sectional view on the line 5—5 of Fig. 1. Fig. 6 is a fragmentary sectional view on the line 6—6 of Fig. 4.

Similar reference characters indicate corresponding parts throughout the several views in the drawing.

Referring to the drawing in detail, the square comprises a try-square section 5 preferably formed from flat metal, and a pair of straight sections 6 and 7 respectively, which may be of any desirable length, and are preferably formed from metal, although these sections 5, 6 and 7 can be made from 50 any other suitable material.

The sections 5 and 6 in one face thereof are milled out to form seats 8 of a depth corresponding to the thickness of the section 5, and also are of a width and length 55 corresponding to the branches of the section 5 so as to snugly receive the same. The sec-

tion 6 has its seat 8 extended at right angles through one longer edge thereof for communication with the seat 8 in the section 7 when the said sections 6 and 7 are positioned 60 at right angles to each other as shown in Fig. 1 of the drawing, and are fastened to the section 5 in a manner presently described.

Mounted for sliding movement in the sections 6 and 7 at the meeting ends thereof and rising from the seats 8 therein are headed pins 9, while formed in the section 5 are substantially key-hole shaped slots 10, through the larger end of which are adapted 65 to pass the heads of the pins 9 so that the latter will engage the narrow portions of the slots 10 when the section 5 is being joined to the sections 6 and 7, the ends of the section being formed with pairs of sockets 11 70 for receiving retaining pins 12 fixed in the sections 6 and 7 to project into the seats 8 at the closed end walls thereof so that the section 5 will be firmly held in the seats 75 when joined to the sections 6 and 7 as shown 80 in Fig. 1 of the drawing.

It will be noted that when the sections 6 and 7 are separated and disengaged from the section 5 they may be used as rules, while the section 5 can be used as a try-square. It is of course to be understood that the sections 6 and 7 have printed or otherwise marked thereon suitable scales for measuring purposes. It will be noted that the sections 6 and 7 are formed with elongated slots 13 in which move the headed pins 9 for permitting the convenient fastening and unfastening of the parts of the device. 85 90

From the foregoing it is thought that the 95 construction of my invention will be clearly understood, and therefore a more extended explanation has been omitted.

What is claimed is:

1. A tool of the class described comprising a try-square section, a pair of separable sections of considerably greater length than the limbs of the try-square section, one end of one separable section adapted to abut one longer edge of the other separable section 100 at one end thereof, each separable section having a seat closed at one end, the seats in the said sections merging into each other on the abutment of the said sections and adapted to receive the try-square section, headed 105 members mounted in the separable sections 110 and engageable in the try-square section, and

retaining pins projecting from the closed end of each seat for engaging in the corresponding end of the try-square section to hold the same in the seats when the headed members are engaged with the said try-square section.

2. A tool of the class described comprising a try-square section having key-hole-shaped slots, a pair of separable sections each having a seat with one closed end for receiving the try-square section, headed pins on the separable sections and respectively engageable in the key-hole-shaped slots, and

retaining pins projecting from the closed end of each seat for engaging in the corresponding end of the try-square section to hold the same in the seats when the headed pins are engaged in the slots in the latter section. 15

In testimony whereof I affix my signature 20 in presence of two witnesses.

GEORGE H. GOUGER.

Witnesses:

ROY L. FERGUSON,

EDWARD CUTTY ALLARDICE.
